UNITED STATES PATENT OFFICE.

LOUIS F. RICHER, OF MONTREAL, QUEBEC, CANADA.

WINDOW.

1,264,334.

Specification of Letters Patent. Patented Apr. 30, 1918.

Application filed October 28, 1916. Serial No. 128,145.

To all whom it may concern:

Be it known that I, LOUIS F. RICHER, a subject of the King of Great Britain, residing at Montreal, in the Province of Quebec, 5 Dominion of Canada, have invented new and useful Improvements in Windows, of which the following is a specification.

In order to more clearly disclose the construction, operation, and use of the invention, reference should be had to the accompanying drawings forming part of the present application. Throughout the several figures of the drawings like reference characters designate the same parts.

15 In the drawings:

Figure 1 is a front view of the invention, applied, with the window casing partly removed to show the counter balancing devices;

20 Fig. 2 is a cross section on line 2—2 of Fig. 1, with the lower sash raised and swung partly open;

Fig. 3 is an enlarged horizontal cross section through the counter balancing devices,

25 Fig. 4 is a side view of Fig. 3.

Fig. 5 is a cross section through the meeting rails,

Fig. 6 is a perspective view of the rack guide, and,

30 Fig. 7 is a like view of the rack-plate.

The main objects of the invention are to provide a simple, compact, efficient, durable, and economical window which will be both weather tight and rattle proof.

35 Another object is to provide a double window construction which may be manipulated as a single window, avoiding the necessity of removing a complete set of windows each spring and replacing them each autumn,

40 with the accompanying problems of storage and maintenance. Another object is to provide a double window construction in which the outer sash may be easily and quickly moved away from the inner sash for cleaning

45 purposes, and then as readily made fast to the inner sash to operate therewith, as a unitary device. Other objects will appear from the following detailed description and claim.

Referring to the drawings in detail, 1 indicates an inside lower sash which is cut away throughout its entire edge to form a ledge 2

and a shoulder 3. Coöperating with this inside sash is an outside or double sash 4 having its entire edge cut away to form a shoulder 5 and a ledge 6. The shoulder of the 55 inside sash rests against the ledge of the outside sash and the shoulder of the outside sash rests against the ledge of the inside sash, so that the frame of the inside sash is nested within the frame of the outside sash, the 60 shoulder of each engaging the shoulder of the other. At one vertical edge they are connected by suitable hinges 7 so that the outer sash may be swung toward or from the inside sash, to permit cleaning of the panes. 65 When closed together, or nested, as in full lines in Fig. 2, the two sashes may be manipulated as one and they will always be kept exactly alined as though they were a single sash.

70 The inside sash is hinged to the inside vertical edge of a sliding plate 8 which is provided with a T shaped rack 9 extending its entire length and slidably mounted in the channel 10 of a guide plate 11 suitably fixed 75 to the inner vertical wall of the window frame. This guide plate is extended inwardly beyond the channel 10, as at 12, to engage behind the head of the T of the rack 9 and retain it in the channel 10—see Fig. 3. 80 Near the upper end of the channel, the guide plate is provided with a slot or opening 13 through which extends a small gear wheel or cog 14 which meshes with the rack 9. This cog is journaled in a small axle 15 with 85 roller bearings 16 interposed between it and the axle. This axle is formed with two shoulders 17 and 18, each shoulder being about one third of the length of the axle from the nearest end, making each third of the 90 axle of a different diameter. The third of least diameter is screw threaded to receive a threaded washer 19 which may be locked in position by a pin 20 passed through the axle directly behind the washer. This washer 95 holds the roller bearings in place between the cog and the middle section of the axle, the first shoulder on the axle acting as a stop for the washer. At the opposite face of the cog is a second washer 21 engaging the second shoulder of the axle and the opposite ends of the roller bearings. Thus, the two

washers form a cage for the roller bearings. About midway of the height of the window frame, the filling block 22 is cut out to receive the cog—see Figs. 3 and 4—and slotted for insertion of the axle ends, as indicated in dotted lines in Figs. 1 and 4. To withstand the strain on the cog and its axle, a strong U shaped metal bracket or strap 23 is provided, its outer ends being slotted to receive the ends of the axle and small filling blocks 24 being provided to fill the slots and fit about one half of each end of the axle and complete the bearings. In practice, the axle with its cog is slipped into place 10 in the filling block 22, then the bracket is slipped into place about the axle ends and solidly secured by screws or the like 15 passed through holes therein and turned into the filling block 22. Then the filling blocks 20 24 are slipped into the slots in the bracket and similarly secured in place. Between the bottom or closed end of the bracket and the outer edge of the cog is a considerable space 25 through which travels the vertically movable counter balance weight 26 provided with a rack 27 which engages and meshes with the outer edge of the cog. This weight is rectangular in cross section and has a snug 30 sliding fit in the space between the cog and bottom of the bracket. Thus, the bracket acts as a guide for the weight and, also, as a means for keeping it in engagement with the rack of the counter weight. The weights are made hollow so that they may be varied 35 to suit circumstances, as clearly indicated in Fig. 2. From the preceding description it will be seen that by removing the screws of the bracket, the counter weight, bracket, and cog may all be removed without disturbing 40 the sashes. Or, by removing the fastenings of the plate 11, the guide plate, sliding rack, and nested sashes may be removed as one combination, without disturbing the other parts.

45 The upper pair of sashes and its counterbalancing devices are the same as just described for the lower pair and, therefore, need not be further detailed here, except, of course, that the slot in the channel of the guide plate is 50 near the lower end instead of near the upper end, and the counter weight is made slightly heavier than the sash to keep it raised, instead of being slightly lighter, as in the case of the lower sashes.

55 To make a perfectly weather tight joint around the vertical edges of the lower sashes, and at the bottom, thin strong metal weather strips 28, 29, and 30 are provided. The two strips 28, at the left of the frame 60 fit snugly into very narrow and comparatively deep kerfs or grooves 31, extending the entire length of the left hand edge of each sash. The strip 29 fits snugly into a similar groove extending across the entire

width of the bottom edge of the outside 65 sash. If desired, two such strips and grooves may be used, one in each sash, instead of only one. The strip 30 is formed as a thin narrow flange at one edge of the sliding plate 8, and fits snugly into the kerf 70 or groove 32 in the vertical face of the right hand side of the outside sash. These strips, fitting snugly into the grooves of the sashes make a perfectly weather tight construction, throughout, and, at the same time, 75 make a perfectly rattle proof noiseless window. There is absolutely no chance for vibration or rattling movement of the sash.

The strips 28 extend to within a very short distance of top of the bottom sashes. 80 When it is desired to swing the lower sashes horizontally inward, it is only necessary to raise them in the usual way, until their lower edges clear the tops of the strips 28 and then swing them in. As soon as they 85 clear the strips 28 they may be lowered, if desired.

For the upper pair of sashes there are corresponding weather strips 33, 34, and 35 and corresponding co-operating grooves or 90 kerfs in the sashes. The strips 33 extend downwardly to within a short distance of the lower edge of the upper sashes. So, to swing the upper sashes inwardly, it is only necessary to lower them until their upper 95 edges pass below the lower ends of the weather strips, and then swing them in. But, in this lowered position, the upper sashes must be able, also, to clear the strips 28. Consequently, the framing and sashes 100 of the upper sashes are made just that much narrower than the framing and sashes of the lower sashes—see Fig. 2.

The meeting rail of the inside top sash and the meeting rail of the outside lower 105 sash each carry a U shaped weather strip 36 adapted to interlock, each with the other, as the two pairs of sashes are completely closed.

This completes the weather tight closure 110 entirely around and between the two pairs of sashes.

It is thought that the construction, operation, and use of the invention will be clear 115 from the preceding detailed description.

Changes may be made in the construction, arrangement, and disposition of the several parts of the invention, within the scope of the appended claim, without in any way departing from the field and scope of the invention, and it is meant to include all such 120 within this application, wherein only a preferred form has been disclosed.

Having thus described my invention, what I claim and desire to protect by Letters Patent is:—

In combination, an inside sash, an outside sash adapted to be nested therein and pro-

vided with a groove in one vertical edge, a sliding plate provided with a flange adapted to be seated in said groove and having a T head provided with a rack, hinge connections between said plate and said inside sash, hinge connections between said inside and said outside sashes, a pinion engaging

and operating said rack, means for driving said pinion, and means for guiding said rack.

10

Signed at Montreal, Province of Quebec,
this 20th day of October, 1916.

LOUIS F. RICHER.
